UNITED STATES PATENT OFFICE

CLAIR H. THOMPSON, OF LOS ANGELES, CALIFORNIA

RACK FOR HANDLING LOCOMOTIVE CABS

Application filed April 2, 1930. Serial No. 440,981.

My invention pertains to a rack which is especially adapted to handle locomotive cabs when it is desired to shift the cabs after removal from the locomotive, from one place to another. The rack is shaped to engage the sills of the cab and an elevator truck may be backed underneath the rack and then utilized to lift the rack with the cab and shifted to the desired place for any work that may be in hand. If desired then, the cab may be supported on blocking and the elevator truck with the rack lowered, thus removing the rack.

A feature of my invention is the construction of a rack with comparatively low side marginal portions and an elevated center portion. The marginal side portions have shoes to bear on the floor of the shop and the center portion is constructed to center the rack on the table or platform of the lifting truck. Another feature of the rack is that the end portions are extensible and may be shifted outwardly slightly to accommodate cabs of somewhat different widths.

My invention is illustrated in connection with the accompanying drawings, in which,

Fig. 1 is a side elevation showing the rack on an elevating truck with a locomotive cab indicated on the rack;

Fig. 2 is a plan of the rack taken in the direction of the arrow 2 of Fig. 3;

Fig. 3 is a side elevation taken in the direction of the arrow 3 of Fig. 2;

Fig. 4 is an end elevation taken in the direction of the arrow 4 of Fig. 2;

Fig. 5 is a detail vertical section on the line 5—5 of Fig. 3 in the direction of the arrows.

The major portion of the rack can be made of material which is usually considered as scrap in railroad yards and has as main structural elements, two main side beams 11. These are preferably formed of old steel rails and there is a top section 12, a sloping section 13 and marginal sections 14. Positioned below the center portion 12 of each rail there is a secondary or supporting rail 15. This is welded or otherwise attached to the sloping section 13. There are a pair of marginal lugs 16 secured to the

undersurface of the rails 15 and the space between these lugs is but slightly greater than the width of the platform on an elevating truck.

There are tie bars 17 extending between the rails, these being illustrated as through the upper section 12 adjacent the corners with the section 13 at the junction line of the sections 13 and 14 and also tie bars through the rails 15. Secured underneath the rail sections 14 there are a pair of legs 18, these being tubular, formed of pipe. At the bottom of the legs there are shoes 19 made of metal plates turned up at the ends. These shoes give a relatively large bearing area and the legs may be made of different heights according to the general height of the rack above the ground.

The side extensions are made by having a slot 20 in each of the rail sections 14 and on each side of these rails there are metal side straps 21 somewhat in the form of fish plates with a bridging strap 22 at the top. The bridging straps may be welded together and there is a bolt 23 extending through the side straps through the slot 20 so that the side straps with the bridging piece may be slid outwardly or inwardly on the rail end sections 14. Connecting these extensible portions there is a bolting plate 24 secured to the outer ends of the slideable side strap and bridging straps and extending between the rails at opposite ends of the rack. These are utilized to support the sills of the locomotive cab and such sills may be bolted to the plate 24.

The manner of using the rack may be considered substantially as follows: In railroad repair yards there is generally a cab department where repairs to the cabs and overhauling of such cabs is done, independently of overhauling and repairs to the locomotive. A lift truck is utilized to transfer the cabs from the locomotive to the cab department. Such lift truck may have its platform lowered and run underneath the center part of the rack so that the platform of the truck when raised will engage the lower rail 15 with the lugs engaging opposite sides of the platform and thus center-

ing the rack. The platform of the truck is then raised and the rack is moved to a location near a crane so that the locomotive cab may be lifted from the locomotive and placed on the rack. Before being placed on the rack the side extensions are moved outwardly and the cab is lowered, resting on these extensions. The truck may then convey the cab to the cab department and after positioning it in a suitable location, the cab is supported by blocking. The truck platform is then lowered, disengaging the ends of the rack from the cab and the extension ends are then thrust inwardly so that the truck with the rack thereon may be moved out from underneath the cab; the blocking of the cab being at the outer side portions. When it is desired to replace the cab on the locomotive, the truck with the rack thereon and the side extensions thrust in, is run underneath the cab. The extensions are pulled out and the platform of the truck raised, thus lifting the cab off the blocking, whence it may be taken to a crane and hoisted on to the locomotive. The side extensions therefore facilitate removal of the rack from a blocked up cab and also facilitate replacing the rack underneath the cab on its blocking. The blockings manifestly should be placed at the side of the cab so that when the extensions are drawn in they will clear the blocking.

Various changes may be made in the principles of my invention without departing from the spirit thereof as set forth in the description, drawings and claims.

I claim:—

1. A rack comprising a frame having a pair of transverse beams, each beam having a central elevated portion, downwardly inclined side portions and depressed horizontally extending lateral portions, the said beams being connected by stay tie bars, means on the depressed end portions of the beams to support a locomotive cab, supporting legs for the end portions of the beams, and means connected to the center portion of the beams to receive and to bear upon an elevating truck.

50 2. A rack, comprising in combination a pair of beams, each having a central elevated portion, downwardly inclined side portions and outwardly extending depressed end portions with supporting legs connected to the end portions, tie bars connecting the beams, each of the beams at the central portion having a secondary or supporting rail connected thereto, the said rail being adapted to receive and to bear upon the platform of an elevating truck.

3. A rack, comprising in combination a pair of beams, each having a central elevated portion, downwardly inclined side portions and outwardly extending end portions with tie bars between the beams and

bolting plates between the end portions, legs connected to the end portions, the center portion having a supporting structure with spacing lugs connected thereto, the supporting structure being adapted to receive and to bear upon the platform of an elevating truck and the lugs to engage opposite sides of the said truck.

4. A rack as claimed in claim 3, the end portions of the beams having sliding extensions with means to limit the outward and inward movement of the said sliding extensions.

5. A rack having a pair of beams, each having a central elevated portion, side downwardly inclined portions and horizontally extending end portions with legs having shoes connected to the end portions, tie bars connecting the beams, each beam having a supporting rail below the central portion and connected to the side portions, and each rail having a space for spacing lugs, the supporting rail being adapted to receive and bear upon the platform of an elevating truck and the lugs to engage the sides of such truck.

6. A rack as claimed in claim 5, sliding extensions on the ends of the beams, said extensions having side straps with bridging pieces above the ends of the beams, and means to limit the outward and inward sliding movement of said extensions.

7. A rack, comprising a pair of beams, each having an elevated central portion, downwardly and outwardly sloping side portions and horizontally extending end portions, a leg extending downwardly from each of the end portions, having a shoe thereon, slidable extensions on the end portions having a pair of side straps, and a bridging piece with a slot and bolt connection to the beam ends, to limit the outward and inward movement of said extensions, a supporting rail positioned below each beam and secured to the sloping portions, each supporting rail having spacing lugs, tie bars connected between the beams and bolting plates secured between the sliding extensions.

8. A rack comprising a frame having a plurality of transverse beams, each beam having a central elevated portion, a downwardly extending side portion with depressed horizontally extending lateral portions, means on the depressed end portions of the beams to support a load, supporting legs for the end portion of the beams, and means connected to the center portion of the beams to be supported and bear upon an elevating truck located underneath the central elevated portion.

9. A rack having a frame with a central elevated portion, downwardly extending side portions with horizontally and laterally extending portions, the said laterally extending portions being adapted to support a

load, and the central portion being adapted to be supported upon and carried by an elevating truck inserted underneath such central portion.

5 10. A rack as claimed in claim 9, the horizontally and laterally extending portions having an outwardly slidable connection whereby the load may be carried with such portions extended and after blocking 10 up of the load the said portions may be withdrawn inwardly to allow removal of the rack and the truck from underneath the load.

11. A rack comprising a frame having a central elevated portion, downwardly extending side portions, and horizontally extending lateral portions, the said lateral portions having floor engaging and supporting means and side extensions having a sliding connection with the lateral portions, said extensions being adapted to support a load when drawn outwardly and to be withdrawn inwardly after blocking up of the load to 20 allow removal of the rack, and the central portion being adapted to be supported by a 25 lift truck inserted underneath.

12. A rack comprising a frame having a central elevated portion, downwardly and outwardly inclined side portions and depressed horizontally extending lateral portions, the said lateral portions having legs, the central portion having means underneath the same to be supported by a lift truck, and side extensions mounted on the lateral portions and slidably thereon adapted to support a load when extended outwardly, and after blocking up of a load said extensions being withdrawn inwardly to 30 allow removal of the rack with a truck underneath the load.

40 In testimony whereof I have signed my name to this specification.
